UNITED STATES PATENT OFFICE
Application September 21, 1944, Serial No. 555,079
3 Claims. (Cl. 131—210)

The present invention relates generally to pipes. More particularly the invention relates to that type of pipe which is adapted for use in connection with smoking of tobacco and comprises a bowl with a tubular stem leading therefrom and in addition a mouthpiece which has a longitudinal duct and is removably connected to the end of the stem that is remote from the bowl.

One object of the invention is to provide a pipe of this type which is an improvement upon and has certain advantages over previously designed pipes and is characterized by the fact that the mouthpiece has an extension which fits within the adjacent end of the stem and has simple and novel means for cooling the smoke as it passes from the bowl to the mouthpiece and also collecting tar and other substances resulting from use of the pipe.

Another object of the invention is to provide a smoker's pipe of the last mentioned character in which the extension embodies a longitudinal series of horizontal open ended holes which define compartments with cross-partitions therebetween and the partitions have centrally disposed aligned apertures therein which serve serially to connect the chambers so that the smoke travels successively therethrough preparatory to entering the longitudinal duct in the mouthpiece.

Another object of the invention is to provide a smoker's pipe of the type and character under consideration in which the mouthpiece extension within the stem embodies a longitudinal series of spaced apart open ended bottom holes which are located at the bottom of the chambers and form wells for collecting the tar, condensate, juices and other material resulting from smoking of the pipe.

A further object of the invention is to provide a smoker's pipe of the last mentioned character in which the portion of the stem that is adjacent the forward end of the extension has a sleeve-like projection which fits tightly within a central aperture in the forward end of the mouthpiece extension and forms a seal whereby the liquid material which collects between the extension and the stem is precluded from flowing back into the bowl.

A still further object of the invention is to provide a smoker's pipe which is sanitary, may be manufactured at a low and reasonable cost and is capable of being readily cleaned.

Other objects of the invention and the various advantages and characteristics of the present pipe will be apparent from a consideration of the following detailed description.

SMOKER'S PIPE

Elmer R. Schwinn, Chicago, Ill.

Application September 21, 1944, Serial No. 555,079

3 Claims. (Cl. 131—210)

2

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a vertical longitudinal section of a pipe embodying the invention;

Figure 2 is a horizontal section on the line 2—2 of Figure 1;

Figure 3 is a perspective of the sleeve part of the stem;

Figure 4 is a perspective of the extension equipped mouthpiece; and

Figure 5 is a transverse section on the line 5—5 of Figure 1.

The pipe which is shown in the drawing constitutes the preferred form or embodiment of the invention. It is designed for use in connection with smoking of tobacco and as its principal parts or components embodies a bowl 6, a composite stem 7 and a mouthpiece 8.

The bowl 6 is formed of wood or any other suitable material and is adapted to be charged with tobacco.

The stem 7 projects laterally from the base of the bowl and consists of a tubular part 9 and a sleeve part 10. The tubular part 9 is preferably formed integrally with the bowl and embodies a centrally disposed longitudinal duct 11 which leads from, and communicates with, the bottom portion of the bowl interior. The rearward end of the tubular part 9, i. e., the end that is remote from the bowl, embodies a centrally disposed longitudinally extending open ended cylindrical socket 12. The sleeve part 10 of the composite stem 7 is formed of hard vulcanized rubber or any other suitable material. It has a cylindrical inner periphery and embodies at one end thereof an integral crosswall 13. Such cross wall abuts against the rearward end of the tubular part 9 of the stem and embodies an integral forwardly projecting stem-like part 14 which fits snugly within the cylindrical socket 12 and forms a removable connection between the two parts 9 and 10 of the stem. In addition to the sleeve-like part 14 the crosswall 13 of the sleeve part 10 of the stem embodies a rearwardly extending projection 15. This projection is aligned with the stem-like part 14 and has the periphery or external surface thereof tapered away from the bowl 6. A longitudinal duct 16 is formed in the stem-like part 14, the crosswall 13

and the projection 15 of the sleeve part 10, and this duct is aligned and in communication with the duct 11 in the tubular part 9 of the stem 7.

The mouthpiece 8, like the sleeve part 10 of the stem, is formed of hard vulcanized rubber or other suitable material. One end portion of the mouthpiece is flattened and has a longitudinal centrally disposed smoke duct 17 therein. Such end portion of the mouthpiece is adapted to be inserted into the mouth of the user of the pipe and has at its rearward extremity an enlarged lip 18. The other end portion of the mouthpiece is in the form of an integral cylindrical extension 19 which fits snugly within the sleeve part 10 and is of such length that its forward end or extremity abuts against the crosswall 13 of the sleeve part 10 of the stem. The central portion of the mouthpiece is cylindrical, as shown in Figure 4, and is of greater diameter than the extension in order to provide an annular shoulder 20 which abuts against the adjacent end edge of the sleeve part 10. The extension 19 embodies a longitudinal series of spaced apart, horizontal, open ended, cylindrical holes 21 and these are of but slightly less diameter than the extension and form smoke chambers 22 with cross-partitions 23 therebetween. The forwardmost partition embodies a centrally disposed, outwardly tapered aperture 24 in which the tapered projection 15 fits snugly, as shown in Figures 1 and 2. The other cross-partitions are provided with aligned, centrally disposed apertures 25 which serve serially to connect the chambers 22. The forward end of the duct 17 leads to, and communicates with, the rearwardmost chamber 22. When suction is applied to the mouthpiece 8 in connection with smoking of the pipe the smoke resulting from burning of the charge of tobacco in the bowl 6 flows first through the duct 11 in the tubular part 9 of the stem 7, then through the duct 16, then successively through the chambers 22 and finally through the duct 17. Due to the fact that the partitions are formed by the cylindrical holes 21 the surfaces thereof that face the chambers 22 are vertically curved. When the smoke in passing through the chambers strikes the aforementioned vertically curved surfaces it tends to swirl and flow outwards into contact with the portions of the sleeve part 10 that are at the ends of the holes 21. As a result of contact of the smoke with such portions of the sleeve part 10 the smoke is cooled. In addition to the horizontal cylindrical holes 21 the extension 19 of the mouthpiece 8 is provided with a longitudinal series of spaced apart, circular bottom holes 26 and a longitudinal series of spaced apart circular top holes 27. The bottom holes are open ended. They lead from the bottom portions of the chambers 22 and define wells in which collect the tar, condensate, juices and other liquid material resulting from smoking of the pipe. The top holes 27 are open ended and lead upwards from the upper portions of the chambers 22 to the superjacent or top portion of the sleeve part 10 of the stem. In connection with swirling of the smoke in the chambers 22 the top holes 27 permit a portion of the smoke to flow upwards into contact with said superjacent portion of the sleeve part 10 for cooling purposes. The holes 26 and 27 are preferably the same in diameter and are formed by drilling the extension transversely. The diameter of said holes 26 and 27 is approximately half that of the holes 21.

In operation of the pipe the smoke, as heretofore pointed out, flows from the bowl first through

the ducts 11 and 16, then successively through the chambers 22 and thence through the smoke duct 17 in the flattened end portion of the mouthpiece 8. During flow of the smoke through the chambers the liquid material, such as tar and condensate, resulting from smoking collects in the wells which are formed by the bottom holes 26 and the smoke, as the result of swirling within the chambers, is cooled by being brought into contact with the side and upper portions of the sleeve part 10. As a result of the fact that the smoke flows successively through the chambers the smoke emanating from the mouthpiece 8 is cool and free from foreign matter. When it is desired to clean the extension 19 the mouthpiece 8 is removed from the sleeve part 10 of the stem 7.

The herein described smoker's pipe is sanitary and may be produced or manufactured at a low and reasonable cost. It effectively and efficiently fulfills its intended purpose and, due to the construction and design of the mouthpiece extension, gives the user what is known as or termed a "cool" smoke.

The invention is not to be understood as restricted to the details set forth since these may be modified within the scope of the appended claims without departing from the spirit and scope of the invention.

Having thus described the invention what I claim as new and desire to secure by Letters Patent is:

1. In a smoking device embodying a tubular stem with tobacco holding means at one end thereof, and a mouthpiece in longitudinal alignment with the stem and with a longitudinal smoke duct therein, an elongated extension connected to the forward end of the mouthpiece, fitting snugly within said stem, and provided with a longitudinal series of spaced apart, open ended, large sized holes having their longitudinal axes parallel and horizontal and forming a series of chambers with cross-partitions therebetween, and also provided with a longitudinal series of open ended bottom holes leading directly downwards from the chambers and forming wells, said partitions having apertures in the central portions thereof for the passage of smoke successively through the chambers, and the rearwardmost chamber being in communication with the forward end of the smoke duct in the mouthpiece.
2. In a smoking device embodying a tubular stem with tobacco holding means at one end thereof, and a mouthpiece in longitudinal alignment with the stem and with a longitudinal smoke duct therein, an elongated extension connected to the forward end of the mouthpiece, fitting snugly within said stem, and provided with a longitudinal series of spaced apart, open ended, large sized holes having their longitudinal axes parallel and horizontal and forming a series of chambers with cross-partitions therebetween, and also provided with a longitudinal series of open ended, top holes leading directly upwards from the chambers, said partitions having apertures in the central portions thereof for the passage of smoke successively through the chambers, and the rearwardmost chamber being in communication with the forward end of the smoke duct in the mouthpiece.
3. In a smoking device embodying a tubular stem with tobacco holding means at one end thereof, and a mouthpiece in longitudinal alignment with the stem and with a longitudinal smoke duct therein, an elongated extension con-

5 nected to the forward end of the mouthpiece, fitting snugly within said stem, and provided with a longitudinal series of spaced apart, open ended, large sized holes having their longitudinal axes parallel and horizontal and forming a series of chambers with cross-partitions therebetween, and also provided with a longitudinal series of open ended bottom holes leading directly downwards from the chambers and forming wells and a longitudinal series of open ended top holes leading directly upwards from the chambers, said partitions having apertures in the central portions thereof for the passage of smoke successively through the chambers, and the rearward-most chamber being in communication with the forward end of the smoke duct in the mouthpiece.
